UNITED STATES PATENT OFFICE

106,291

DESIGN FOR A HAMPER

Emil A. Florang, Burlington, Iowa

Application May 12, 1937, Serial No. 69,325

Term of patent 3½ years

To all whom it may concern:

Be it known that I, Emil A. Florang, a citizen of the United States of America and resident of Burlington, in the county of Des Moines and State of Iowa, have invented a new, original, and ornamental Design for Hampers, of which the following is a specification, reference being had to the accompanying drawing, forming part thereof.

The figure is a perspective view of a hamper, showing my new design.

The opposite end and the rear side of the hamper are substantially the same as the end shown in the drawing.

I claim:

The ornamental design for a hamper, as shown and described.

EMIL A. FLORANG.
